ATTORNEY

UNITED STATES PATENT OFFICE

OLOF BJORK, OF TAFT, BRITISH COLUMBIA, CANADA

CATTLE GUARD

Application filed May 31, 1929. Serial No. 367,331.

This invention relates to improvements in cattle guards of that type adapted to be placed between and alongside the rails of a railway track adjacent the railway crossings to prevent or deter cattle from walking along the railway right of way. One object is to provide a guard that is positive in use, that is durable and that is so constructed that broken or worn parts may be readily replaced when necessary.

With the foregoing and other objects in view the invention consists in the combination and arrangement of parts to be hereinafter fully described, pointed out in the claim and illustrated in the accompanying drawing which forms a part of this application for patent and in which—

Fig. 1 is a fragmentary plan view of a railway right of way illustrating the application 20 of the cattle guard.

Fig. 2 is a cross sectional view through Fig. 1 enlarged.

Fig. 3 is a vertical sectional view through one of the spur wheels and frame.

Fig. 4 is a central sectional view through a modified form of spur wheel.

Fig. 5 is a view of one of the spurs.

Like reference characters denote corresponding parts throughout the several views.

The cattle guard comprises a plurality of parallel shafts supported by parallel stringers, each shaft being provided with a plurality of spur wheels, the spur wheels of one shaft being staggered with relation to those of the next shaft, the spurs of each spur wheel being either of the integral type or loose spurs mounted upon a hub, the ends of which are flanged to hold the spurs in place.

The reference numerals 1, 2 denote the 40 stringers each of which is provided with a metal strip 3 secured thereto by fasteners 4, said strips comprising a plurality of bearings 5 in which are disposed the ends of the parallel shafts 6 that connect the said stringers.

Loose upon each shaft are a plurality of spur 45 wheels 7, the spur wheels of one shaft being staggered with relation to those of the next shaft. The spur wheels may be of the type shown in Fig. 3 in which the spurs 8 are integral, the several wheels being loose upon their

shafts and separated by the collars 9, or the spur wheels may be of the type shown in Fig. 4 comprising a plurality of spurs 10, 11, 12, 13 and 14 loose upon the hub 15 that terminates in the flanges 16, 17 that cooperate to secure 55 said spurs together. The several spurs are formed each with a perforation 19, the several perforations of the several spurs being aligned to permit passage of the locking pin 18 that extends through all of said spurs to 60 keep them in operative position. In the event that one spur becomes broken the pin 18 may be removed and a new spur inserted in place of the broken one and the pin then replaced.

The stringers 1, 2 are spaced apart at right 65 angles to the railway rails 20, 21 adjacent the railway crossing and should the animals attempting to walk down the tracks from the crossing step upon the spur wheels which make their walking so difficult, laborious and 70 uncomfortable that they leave the track.

What is claimed is:—

In a cattle guard, a framework, shafts carried thereby, spur wheels arranged upon each of said shafts, each spur wheel comprising a hub formed with flanged terminals, spurs loose upon said hub, each spur being formed with a perforation, and a locking pin connecting the apertured portions of the 75 spurs of said hub.

In testimony that I claim the foregoing as my own I have hereto affixed my signature.

OLOF BJORK.
